PRINTING TELEGRAPH SYSTEM AND APPARATUS

Albert H. Reiber, Evanston, Ill., assignor to Teletype Corporation, Chicago, Ill., a corporation of Delaware

Application December 31, 1935, Serial No. 56,919
Renewed June 5, 1939

50 Claims. (Cl. 178—25)

The present invention relates to printing telegraph systems and apparatus.

Objects of the present invention are to provide, in a remotely controlled telegraph printing machine, apparatus for determining the phase relationship of the printing platen, and means for automatically and selectively ejecting lengths of printing material and for thereafter severing the ejected length of said material from a stock or supply roll.

Another object of the invention is to provide means at a remote station operative in response to an inquiring signal for informing a transmitting station of its receptive condition.

A further object is to provide means at a remote station selectively responsive to a received signal for operating a key-lever thereat to initiate the transmission of a signal indicative of a particular condition.

A still further object of the invention is to provide means whereby the operator at a transmitting station may have complete control over the apparatus at a receiving station, so that the apparatus at the receiving station may be conditioned by the sending operator either for receiving or sending messages.

To achieve the above and other objects of the invention, a page printer of the type disclosed in U. S. Patent 1,904,164 is arranged with means for determining the synchronization or phasing of the platens of the interconnected printers, as well as means for feeding a predetermined length of record material through a printing apparatus and for cutting off the predetermined length of material automatically. This arrangement is desirable in systems wherein the printing apparatus at the receiving stations remain unattended except for the tearing off the copy, or for attention when the attendant is signalled. The present invention thus provides means whereby the sending operator can determine periodically whether or not the platen of the receiving printer is in exact phased relation with the platen of the sending machine.

Specifically, one embodiment of the invention contemplates the provision of a cam, mounted on the platen shaft and rotatable therewith, which cooperates through a lever arrangement with a special selectable function lever. This function lever is further provided with a forward extension which cooperates with a keylever, so that upon the selection of the special function lever, a keylever of the keyboard is actuated and the transmitter is operated to transmit to the sending station impulses indicative of a

particular condition which notifies the sending operator that the receiving printer is operating correctly. Simultaneously with the actuation of the keylever, the special function lever also operates the send-receive break switch to change the condition of the receiving apparatus from receiving to sending.

Thus, when the special function lever is selected, it performs two functions, first the operation of the send-receive break key, and secondly the operation of a keylever of the keyboard to transmit an answer-back signal to the sending operator. However, the special function lever is not selected, even though the selecting vanes may be set for its selection, unless the platen and its phasing cam are in a predetermined position. When the phasing cam is not in a predetermined position, the selection of the special function lever is prevented and no signal is transmitted, thus indicating to the sending operator, by the failure to receive a response, that the platen of the receiving printer is not in phase with that of the sending or home printer. By the arrangement according to the present invention, a positive signal or indication is transmitted to the sending operator to apprise him of the fact that the platens of the interconnected printers are in phase.

Another feature of the invention resides in the automatic mechanism for severing the record material in predetermined lengths, so as to provide tickets or coupons of predetermined size. Also, multiple copies of such tickets or coupons are produced. According to the embodiment disclosed, any one or more of four rolls of record material may be fed into the printing area under the control of the remote sending apparatus by selecting in the receiving apparatus special function levers according to the number of copies desired. These special function levers control the release of clutch mechanisms to govern the feeding of the record material to the printing zone. After the record material has been so fed, the line-feed mechanism of the receiving apparatus, which has been rendered inoperative during the latter operation, has again been rendered operative to feed the record material line by line until a predetermined length of coupon has been obtained, whereupon the leading edge of the record material acts to establish an electrical circuit for operating automatically the mechanism for severing the coupons, simultaneously with which the coupons are ejected by constantly rotating ejector rollers.

45 50 55 A more comprehensive understanding of the

present invention may be had from the following description, taken in conjunction with the accompanying drawings wherein like characters represent similar parts throughout the several views.

Fig. 1 is a fragmentary elevational view of the apparatus according to the present invention;

Fig. 2 is a fragmentary sectional view taken on line 2-2 of Fig. 1;

The combination sending-receiving unit as set forth in U. S. Patent 1,904,164 comprises essentially a printing apparatus and a keyboard transmitting apparatus. In practice, two or more of such units are interconnected in a telegraphic signal line for intercommunication. Having reference to Figs. 1 to 4, it is observed that most of the parts shown here have their counterpart in the structure illustrated in the noted patent. Although various forms of transmitting mechanisms may be employed, the one chosen to illustrate the present embodiment is in accordance with the transmitter mechanism disclosed in U. S. Patent 1,595,472. As shown in Figs. 1 and 2, the keyboard portion indicated generally as 11 is provided with a set of keys 12 arranged similarly to the well-known typewriter keyboard, and as illustrated in Fig. 2, key-levers 13 associated with the keys 12 are pivotally mounted on a common shaft 14 and are spring held in normal horizontal position by individual springs 15. Arranged transversely below the key-levers 13 in operative relation thereto is a series of five V-notched selector bars 16 which are adapted to be operated permutably, in well-known manner, in accordance with the key depressed.

The selector bars 16 are pivotally articulated to a corresponding series of locking latches 17 (Fig. 1) which are adapted to be rocked to either of two positions thereby. Associated with latches 17 is a corresponding series of contact levers 18 for making and breaking contacts 21. Contact levers 18 coact with individual contact cams 22 mounted on shaft 23. The shaft 23 is provided with a clutch mechanism, not shown,

which is adapted to be controlled by a universal operator as set forth in Patent 1,595,472. The transmitting unit consists essentially of a keylever 13 which terminates in a notched selector bar 16. The rotation of the selector bar 16 is simultaneously with the rotation of selector bars 22 and the locking latches 17. The rotation of the selector bar 16 is controlled by a cam 25 which is permitted to rotate in a clockwise direction (Fig. 1) to effect the locking of latches 17. The setting of the locking notch 17 determines whether the contact levers 18 shall or shall not be affected by their associated cams 22 to cause the opening or closing of their associated contacts 21 to transmit over a signal line, as will appear hereinafter from a description of Fig. 4, to the receiving station a predetermined code combination of signalling impulses. The respective notches in the cams 22 are arranged in a spiral progression so that upon the rotation of the cam assembly, the contacts 21 will be controlled successively. The apparatus herein disclosed is operated in accordance with an equal length letter code, in which each code combination is a permutation of marking and spacing conditions and is preceded by a start impulse and followed by a stop impulse, according to the familiar start-stop system.

The send-receive break mechanism, indicated generally as 26 (Fig. 1), is fully described in Patent 1,904,164 and provides an automatic means whereby the receiving operator may interrupt the sending operator either to have the sending operator repeat part of the transmitted message or as sometimes occurs, the receiving operator may in turn desire to send to the sending operator a message of greater importance or urgency, and so, means has already been provided in accordance with the disclosure in Patent 1,904,164 whereby the receiving operator may interrupt the printer at the other end of the line and begin to transmit his own message. In addition to the features embodied in the send-receive break mechanism according to said patent, the present invention contemplates the provision of means whereby the sending operator may have complete control over the receiving apparatus by automatically conditioning the receiving apparatus not only from a sending to a receiving position but also from a receiving to a sending position by the transmission of predetermined code signals.

This send-receive break mechanism 26 shown in Figs. 1, 2, and 3 is located at the front of the apparatus and substantially to the left to be most conveniently situated for the use of the operator. The send-receive break mechanism, as noted in Patent 1,904,164 consists of two major parts, one of which is located on the base portion 27 of the printing apparatus, and the other part is attached to the printing unit. As indicated, these two parts are separable at 28, member 29 which is shown in Figs. 1 and 3 being equivalent to member 444 (Fig. 27) of Patent 1,904,164. For a description of the manner in which the send-receive break mechanism is conditioned from sending to receiving through the instrumentality of member 29, reference may be had to U. S. Patent 1,904,164.

That part of the send-receive break mechanism which is associated with the base portion 27 comprises a bracket 31 which is fixed to the

base portion and consists primarily of three electrical contact pairs 32, 33, and 34 (Figs. 1 and 4), which may be operated either manually by a lever 30 from a position occupied by the operator of the printing apparatus or automatically by two systems of levers, one system comprising lever member 29 (effective in a manner described in Patent 1,904,164 to condition the mechanism from sending to receiving), and the other system comprising a system of levers effective, as will presently appear, to condition the send-receive break mechanism from receiving to sending. The latter changeover or switching mechanism is one of the salient features of the present invention.

Contact pair 32 is located in the signal line and is used as a "break" contact therein. For example, having reference to Fig. 4, it is observed that contact pair 32 is in the circuit extending from battery 36, conductor 37, contact 38 of the transmitter contacts, conductors 39 and 41, contacts 32 (when closed), relay 42, line wire 43 to the receiving station, thence over a similar circuit at the latter station. Contact pair 33 is so wired as to shunt the sending contacts 21 of the keyboard transmitter, thereby rendering the keyboard ineffective. From Fig. 4 it is obvious that the contact pair 33 is in the circuit extending from battery 36, conductor 37, contact 38, conductor 39, contact 33, and conductor 44 back to battery. Contact 34 is so connected that it may be placed in the circuit of the control magnet 45 of a tape transmitting distributor.

Lever arm 30, Fig. 3, by which that part of the break mechanism which is located on the base portion 27 may be manually operated, can occupy any one of three positions. The intermediate position of this lever arm is illustrated in Fig. 1 and is called the "receive" position; the uppermost position is known as the "break" position, and the lowermost position (which is shown in Fig. 3), is the "send" position. When the lever arm 30 is in the "send" position, contact pair 32 in the line circuit is closed; contact pair 33, shunting the keyboard transmitting contacts is open; and contact pair 34 in the tape transmitter distributor circuit is closed. When lever arm 30 is in the "receive" position, contact pair 32 in the line circuit is still closed; contact pair 33 shunting the keyboard contacts 21 is also closed; and contact pair 34 in the tape transmitter distributor circuit is open. In the extreme upward position of lever arm 30, known as the "break" position, contact pair 32 in the line circuit is opened, thereby breaking the line circuit, and contact pairs 33 and 34 are closed and opened respectively.

Besides being movable manually to each of the three aforementioned positions, lever arm 30 may also be moved automatically from the "send" to the "receive" position and vice versa by means of two systems of levers, mechanically operated, in the printing unit. The send-receive break mechanism is shifted mechanically from the "send" position to the "receive" position by means of the system of levers including lever 29 (Fig. 3). As indicated in Figs. 1 and 3, a lever 35 is pivoted at 45 upon the rear wall of a bracket 31 and is of substantially T-shaped configuration comprising arms 46, 47, and 48. Arm 47 is provided with a laterally disposed portion 49 which coacts with lever 29, while vertical arm 48 is provided with a laterally disposed arm 51 which actuates contact switch 32. Arm 46 of

lever 35 is provided with a laterally disposed portion 52 to which is attached one end of a spring 53, the other end of which is fixed to bracket 31. Arm 46 is also provided with a two-position 5 or double shouldered notch 54 to cooperate with an arm 55 of a lever 56 when lever arm 46 is moved either to its "send" or "receive" position. Appropriately positioned below lever 35 and pivotally connected at 57 to bracket 31 is the three-arm lever 56. Arm 58 of lever 56 cooperates with lever arm 30 and arm 59 is provided with a laterally disposed portion 61 which actuates blades 62 and 63 of contact pairs 33 and 34. To portion 61 is fastened one end of a spring 64, the other end of which is anchored upon bracket 31.

In the illustrated position of lever 35, the line contact 32 remains closed so that the signals coming in over the line can actuate the line relay 42 and hence selector magnet 65 (Fig. 4), 20 and the contact pair 33 is also closed to render the keyboard transmitter inoperative by shunting the transmitting contacts 21. This position is attained, as set forth in Patent 1,904,164, by the operation of lever 29 (Fig. 3), in a counter-clockwise direction upon the reception of two successive identical code signals, which imparts clockwise rotation to lever 35 about its pivot 45 sufficient to permit the arm 55 of lever 56 to escape the left or deeper portion of notch 54. 25 Lever 56 thereupon is rotated slightly in a clockwise direction under the influence of spring 64 to bring arm 55 into engagement with the right-hand portion of notch 54. This movement of lever 56 effects through portion 61 and contact spring 62 the closure of contact pair 33 and opening of contact pair 34. By the rotation of lever 35, arm 49 thereof has not moved sufficiently to open the signal line contacts 32. Lever 35 is shown in Fig. 3 in the "send" position; that 30 is, in a proper position to permit the transmission of signals from keyboard 11. This position is attained automatically in a manner which will now be described.

Lever 56 of the send-receive break mechanism 45 is provided with an extension 66 which cooperates with one arm of a lever 67 pivotally supported on a bracket 68 mounted on the base portion 27 of the unit. The other arm of lever 67 cooperates with a screw 69 adjustably carried in 50 the forwardly extending arm 71 (Fig. 2) of a special function lever 72 pivotally mounted on function lever shaft 73. Function lever 72 normally tends to rotate in a counter-clockwise direction (as viewed in Fig. 2) under the influence 55 of a spring 74 individual thereto, into selective relation with a series of selector vanes 75, but is held against rotation by a function lever bail 76, except during the cyclical operation of the apparatus, as set forth in Patent 1,904,164.

60 At the forward end of arm 71 there is carried an adjustment screw 77 which cooperates with one of the keylevers 13, so that when the function lever 72 is selectively operated upon the proper setting of selector vanes 75, the keylever 65 13 associated therewith will be depressed through the instrumentality of screw 77. Function lever 72 is also provided with a rightwardly extending arm 78 (as viewed in Fig. 2) which cooperates with the end 79 of the depending arm of a bell 70 crank lever 81 (Fig. 1) pivoted to a bracket 82 mounted on a portion 83 of the printer frame. The end of the horizontal arm of bell crank lever 81 is pivoted to one end of a vertically disposed link 84, the upper end of which is pivoted 75 to arm 85 (Fig. 2) of a lever 86 carried on a

pivot shaft 87 disposed between brackets 88 and 89 appropriately supported in the apparatus. Lever 86 is also provided with an arm 91 at the extremity of which is carried a cam follower roller 92 which, due to the action of a spring 90, coacts with a platen phasing cam 93 fixed to a shaft 94 on which a platen 95 is carried.

When the cam follower 92 rests in the depression in the periphery of cam 93, the function lever 72, when selected for operation upon the reception of an allotted code signal, will be enabled to initiate the transmission of a code signal indicative of this fact to the operator at the inquiring station. Where printed forms are employed, it is essential that they be correspondingly positioned in the interconnected printers. To determine this, it is prearranged that the printed forms be placed in the printer in a definite position with respect to the depression in cam 93, so that when the follower rollers 92 at the interconnected stations rest in the depressions of their respective cams 93, the printed forms in each printer will be correspondingly positioned. Thus, when the sending operator observes that the cam 92 of his printer rests in the depression of cam 93, he may operate a certain one of his keylevers which has allotted thereto a code combination corresponding to that to which the function lever 72 responds. Upon the reception of this code signal at the receiving station, the selector vanes 75 will be positioned permutably in a manner set forth in Patent 1,904,164, and as the function lever bail 76, Fig. 2, is oscillated, the spring 74 will draw the function lever 72 towards the vanes 75. Since the vanes are set to correspond to the code cut on the edge of the function lever 72, the function lever 72 will be rotated sufficiently to depress keylever 13 through screw 77, and to transmit a signal to the sending operator to apprise him that the platen of the receiving printer is in phase with the platen of the printer at the transmitting station.

In the event that the cam follower 92 is not found resting in the depression in cam 93; that is, if the platen and hence the printed forms, are not in proper position or phase, the follower roller 92 will dwell on the high part of cam 93, thereby causing lever 91 to assume its counterclockwise position, thus raising link 84, rotating lever 81 counterclockwise (as viewed in Fig. 1) to bring the end 79 thereof into the path of arm 18 of function lever 72, thus blocking its selection and preventing the function lever 72 from responding to the selective disposition of the selector vanes 75. Accordingly, the keylever 13 will not be depressed and no code signal will be transmitted from the receiving station to the sending operator. It is thus seen that if the platens of the interconnected printers are in phase, an answer-back signal indicative thereof will be automatically transmitted by the receiving station in response to an inquiring signal sent by the sending operator, and if the platens are out of phase, lever 81 will block the selection of function lever 72 and no answer-back signal will be transmitted.

As previously indicated, the send-receive break mechanism has to be properly conditioned to permit the transmission of the signal indicative of phased platens. From the disclosure in Patent 1,904,164 it may be observed that a sending operator may condition an interconnected telegraph apparatus for receiving by transmitting thereto two "blank" signals (that is, two code signal combinations composed entirely of spac-

ing impulses) which will, through the instrumentality of lever 29, place lever 35 in the position shown in Fig. 1, in which condition the keyboard contacts 21 are shunted. Now in order that the sending operator may receive in response to his inquiry a signal indicating to him that the platens are in phase, he must be able to control remotely the receiving apparatus so as to condition it to transmit signals; that is, he must open contacts 33 to break the shunt circuit of contacts 21. To accomplish this result, the screw 69 carried by arm 71 of function lever 72, upon the selective operation of lever 72, effects the clockwise rotation of lever 67 which in turn causes the lever 56 to rotate sufficiently in a counterclockwise direction to cause arm 55 thereof to engage the deep portion of notch 54 (as shown in Fig. 3) and to move arm 61 away from the contact spring 62, whereupon contact 33 will open to break the shunt circuit. Simultaneously with the operation of lever 67, as was previously noted, the keylever 13 associated with function lever 72 was depressed, which actuated the selector bars 16 permutably to impart through latches 17 a corresponding setting to contact levers 18, and also the universal bar 96 to initiate the rotation of the transmitting cams 22, whereupon the desired indicatory signal is transmitted over the signal line 43 (Fig. 4) to the sending operator's station.

In addition to the feature of determining the phasing of the platens of interconnected printers, the present invention also provides, as illustrated in Figs. 5 to 11, a severing and ejecting mechanism for the printed forms and a multiple paper feeding mechanism which is solely under the control of the sending operator at a remotely situated station. The arrangement herein disclosed provides for feeding either simultaneously, permutably, or individually one to four copies of record material to the printing zone. The record material may be provided with suitable duplicating means, such as carbonized back, or spot-glued carbon paper. In Fig. 5 is shown the selectively operable clutch release mechanism for the several feed rolls. A predetermined setting of the selector vanes 75 will result in the selection of a special function lever 101, which, upon the rocking of function bail 76 about shaft 102, will respond to the action of its spring 103 to rotate a certain extent in a counterclockwise direction about the function lever shaft 73, thus causing the tail portion 104 to rise, bringing push bar 105 superposed thereabove into the path of the function bail blade 106. Thereafter as function cam 107 rotates on shaft 108, a spring 109 causes blade 106 to move rightwardly and it in turn imparts like movement to push bar 105 which imparts clockwise rotation to a bell crank 111 pivoted on shaft 112, thereby actuating a vertical trip bar 113 downwardly. Bar 113 acts upon a clutch release bell crank 114 to cause its disengagement from a stop disc 115 fixed to feed roll shaft 116, which shaft thereupon is free to make one complete revolution, thus feeding a predetermined portion of record material 117 (Figs. 5 and 6) from supply roll 118.

Push bars 121, 122, and 123 may be brought into operative relation with function lever blade 106 either simultaneously or individually, depending upon whether a common function lever or individual function levers are employed, to operate cell cranks 124, 125, and 126, which in turn through vertical trip bars 127, 128, and 129 operate clutch release bell cranks 131, 132, and

133 to feed record material from rolls 134, 135, and 136, respectively. As the function bail 76 is returned to its normal position by cam 107, the push bars 105, 121, 122, and 123 are restored to their leftward positions by their individual springs 136.

Although line feeding of the printed record is performed in the same manner as set forth in Patent 1,904,164, the feeding of the record material to the printing zone preparatory to printing and cutting a new ticket or coupon is done by power derived from a motor 141 appropriately mounted on the frame 142 (Fig. 7) of the apparatus. The positional relationship of the elements comprising the features of invention herein described, with respect to the structure disclosed in Patent 1,904,164, is indicated in Figs. 6 and 7, having reference to the drum 150 of the carriage return mechanism carried on bracket 160 of the main frame. These parts correspond with parts 223 and 221, respectively, shown in Fig. 6 of Patent 1,904,164. Fixed to the motor shaft 143 is a pinion 144 which through a gear 145 imparts power to a shaft 146 which drives gears 148 individual to each of the feed rolls 149. Gears 148 are connected to the shafts carrying the feed rolls 149 by friction discs 151 (Fig. 7). The ejector rollers 152 and 153 are also rotated by motor 141 through a frictional connection with gear 154 meshed with a pinion 155 carried on a power take-off shaft 156 (Fig. 6), which is rotated by gear 148 through gear 157.

In view of the similarity of the feeding mechanisms associated with rolls 118, 134, 135, and 136, it is necessary that only the arrangement associated with one of the mechanisms (roll 118) will be described in detail. The record material from roll 118 passes between guide plate 158 and guide roller 159, thence between feed roller 149 and pressure roller 161 which protrudes through an aperture in plate 158. The assembly of the pressure rollers 161 for the several feed rollers 149 is shown in Fig. 9, and will be discussed hereinafter. The record material 117 then passes between a lowermost portion of guide plate 158 and a guide plate 162 and thence between guide plate 162 and a bottom plate 163 to the opening or shearing edge 164. The edge of the bottom plate 163 at the opening 164 coacts with a shear blade 165 (Fig. 7) to sever the record material. The record material is guided to the platen 95, carried on platen shaft 94, by guide plate 166 to the printing zone indicated by type bar 167, Fig. 6, thence between guide plates 166 and 168 to the ejector rollers 152 and 153.

A pressure roller 169 (Figs. 6 and 9) cooperates with the platen 95 for the purpose of line feeding the record material during printing. Roller 169 is rotatably supported at one end by one arm of a three-armed lever 171 (Fig. 6) fixedly mounted on a shaft 172, and at the other end by a bell crank lever 173 (Fig. 9) also fixed to shaft 172. Pressure is imparted by roller 169 upon platen 95 through the instrumentality of springs 174 and 175 associated with levers 171 and 173, respectively. Line feeding is accomplished as set forth in Patent 1,904,164 through the instrumentality of a line feed bell crank lever 176 (Fig. 9), which is analogous to lever 251 shown in Fig. 7 of the patent. As stated in the noted patent, the operation or function of line feeding is initiated by the reception of a special code signal which acts through the selector mechanism to select a line feed function lever which controls the operation of line feed

link 177 which rocks lever 176 counterclockwise about its pivot 178 to step a feed pawl 179 along the periphery of ratchet wheel 181 fixed to platen 95 so that a downward movement of link 177 will effect the rotation of platen 95 one angular step in the direction of the arrow.

Shear blade 165 forms one arm of a shearing lever 182 pivoted at 183 (Fig. 7), the other arm 184 of which is articulated to a lever 185 (more clearly shown in Fig. 6) pivotally anchored at 186. Lever 185 is pivoted at 187 to the vertically movable core 188 of a solenoid 189. Arm 184 adjacent lever 171, is provided with a hook 191 adapted to cooperate with arm 192 of lever 171 so that upon the upward movement of hook 191 (due to the clockwise rotation of lever 182, Fig. 7, by solenoid 189), lever 171 will be rotated counterclockwise (as viewed in Fig. 6) until arm 193 thereof becomes latched by lever 194 pivoted at 195. This action of hook 191 upon lever 171 causes the removal of pressure roller 169 from platen 95 to permit the feeding of record material from rollers 118, etc., as will presently appear.

The unlatching of lever 171 is achieved in the following manner. Lever 194 is pivotally connected to a link 196 which is connected to a U-shaped bail 197 pivoted, as indicated in Figs. 7 and 9, on a shaft 198. Portion 199 of bail 197 is provided on its bottom edge with a series of cam projections 201, Fig. 1, which cooperate with a corresponding series of cams 202, one associated with each of the feed rollers 149. Whenever a cam projection 203 on a cam 202 passes under a cam projection 201, the U-shaped lever 197 is rotated in a counterclockwise direction (as viewed in Fig. 7) and as portion 199 thereof is raised, like motion is imparted to link 196, which in turn rotates lever 194 sufficiently in a counter-clockwise direction against the tension of spring 204 to unlatch lever 171, whereupon spring 174 is free to press roller 169 against platen 95, thus rendering the line feed mechanism again effective.

The operating circuit for solenoid 189 is shown diagrammatically in Fig. 7 and is controlled by two contracting rings carried on ejector rollers 152 and 153. The rings 205 and 206 normally complete an energizing circuit for a relay 207 which circuit extends from battery 208, through rings 206 and 205, over wire 209, through winding of relay 207, thence to ground. The armature 211 of relay 207 controls an operating circuit for solenoid 189 which circuit extends from battery 212, through contact 213 (when closed), armature 211, over wire 214, through the winding of solenoid 189, thence to ground. So long as no record material is interposed between rings 205 and 206 the relay remains energized, and the circuit for solenoid 189 remains broken, but when the record material which has been advanced by the line feed mechanism reaches the ejector rollers 152 and 153 and is interposed between rings 205 and 206, the circuit for relay 207 is broken, whereupon armature 211 is released, and upon responding to its spring 215 closes contact 213 to establish the energizing circuit for solenoid 189. The solenoid 189 will remain energized until the severed portion of the record material has been completely ejected by rollers 152 and 153, after which rings 205 and 206 will again come into contact with each other to effect the energization of relay 207, and thereby break the operating circuit for solenoid 189. It is thus observed that the introduction of the record material between rollers 152 and 153 (and hence between rings 205 and

206) is instrumental in effecting the severance of the record material.

Operation

The record material supply rolls 118, 134, 135, 5 and 136 are appropriately supported in the apparatus, and the recording materials therefrom are guided around their respective guide rollers 159, and between their respective feed rollers 149 and pressure rollers 161, and their edges are 10 brought into line with cutting edge 164. Upon receipt of a code signal assigned to function lever 101, the vanes 75 will be set correspondingly and upon initiation of operation of the apparatus under control of the selector mechanism, as described in Patent 1,904,164, the function bail 16 will be rocked, permitting lever 101 to be 15 biased by its spring 103 to cause extension 104 to raise push bars 105, 121, 122, and 123 into operative relation with function bail blade 106 so that when these push bars are pushed rightwardly (as viewed in Fig. 5) bell cranks 111, 124, 125, and 126 will be rotated clockwise simultaneously to operate, through bars 113, 127, 128, and 129, clutch release levers 114, 131, 132, and 133 simultaneously. In this manner, four layers of record material are fed to the printing zone indicated by type bar 167. During this feeding operation, lever 171 (Fig. 6) is latched by lever 194 to hold pressure roller 169 out of engagement with platen 95 to permit free access of the record material therethrough to the printing point. Lever 171 (Fig. 6) and lever 173 (Fig. 9) are fixed to the shaft 172 so that when lever 171 is operated, lever 173 will also be operated to control 30 through a bar 216 a series of levers 217 carrying the pressure rollers 161. The levers 173 and 217 are so articulated by slot and pin connection with bar 216 that when pressure roller 169 is free and therefore operatively effective, pressure rollers 40 161 will be ineffective and vice versa.

Just prior to the end of the aforescribed feeding cycle the bail lever 197 is operated to unlatch lever 171 and to bring pressure roller 169 into action, whereupon in response to successive line feeding operations the record material is advanced toward the constantly rotating ejector rollers 152 and 153. As soon as the ejector rollers are reached and the record material is interposed between the contact rings 205 and 206, the circuit for relay 207 is broken, whereupon the circuit for solenoid 189 is completed and the shearing lever 182 is operated to cause blade 165 to sever the record material. During this latter operation, lever 171 is rotated by member 191 into its latched position, thus separating pressure roller 169 from platen 95. The ejector rollers 152 and 154 are then effective to feed out or eject the coupon or ticket just produced, and the apparatus is thus prepared to receive again the code signal for selecting function lever 101.

Modifications

In the form of the invention illustrated in Fig. 12, the platen phasing feature is controlled directly by a sword 218 of the sword-and-T selector according to U. S. Patent 1,745,633, and which is also shown in Fig. 28 of U. S. Patent 1,904,164. Briefly, this selector mechanism comprises a receiving magnet 219 responsive to line signal impulses over a signal line 221 which extends, in the present embodiment, through the winding of selector magnet 219 to a "break" contact 222 controlled by a relay 223. As disclosed in the aforementioned patents, a selector drum 75

224 operates cyclically in response to start-stop code signals and rotates at a speed in synchronism with the speed of code impulsing, carrying thereon a helically arranged series of cams 225 which cooperate sequentially with a corresponding series of selector levers 226 each of which in turn carries in a ball and socket joint a sword 218 which is provided with abutments 227 and 228 which cooperate with corresponding abutments 229 and 231 on a selector lever 232 which is oscillated according to the marking or spacing impulses received over signal line 221.

The selector lever 232 is shown in Fig. 12 in its marking position in which position it causes sword 218, upon actuation of selector lever 226 by cam 225, to be rotated clockwise against its lower stop 233, thus avoiding the insulation piece 234 of a contact 235. When selector lever 232 assumes its clockwise position in response to a spacing impulse over the line wire, abutment 228 of sword 218 will cooperate with 231 to swing sword 218 counterclockwise against its upper stop 236 into position to collide with contact spring piece 234. Sword 218 acts under the influence of spring 227 associated with selector lever 226 to close the contact pair 235 to complete a local circuit from positive battery through resistance 238, contact pair 235, over conductor 239, through operating winding 241 of relay 223, thence over wire 242 to negative battery. Inserted in this circuit last described is a contact 243 which acts to shunt the operating winding 241 of relay 223. Contact 243 is controlled by a platen phasing cam 244 similarly in its effect to cam 93 shown in Fig. 2.

To determine whether the platens of the interconnected stations are in phase, an operator at the sending station after observing that his platen is in the proper or zero position, transmits a test signal which will operate sword 218 to close contact 235 to establish a circuit through operating winding 241 of relay 223. However, if the platen at the receiving station is in proper position with the platen phasing cam 244 acting to close contact 243, the operating winding 241 of relay 223 will not be effective since it will be shunted out by the circuit through contact 243. If the platen is not in proper phase and the cam 244 is not in a position to close contacts 243, the operating winding 241 will be energized, whereupon the armatures 245 and 246 will be operated, the former to open contact 222 to break the line circuit to indicate to the sending operator that the platens are out of phase and simultaneously armature 246 will close a contact to 247 to establish a bell ringing circuit from positive battery through a manually operated contact 248, armature 246, contact 247, winding of electric bell 249 to negative battery. At the same time, a locking circuit for relay 223 is established from positive battery through contact 248, armature 246, contact 247, locking winding 251 to negative battery. In this manner, by the ringing of alarm bell 249, the attendant at the receiving station is notified that the apparatus at the local station is in need of attention. To restore the relay 223 to its normal unenergized condition after attending to the alarm, the attendant will manually break contact 248, thereby opening the locking circuit for relay 223, permitting contact 222 to close to establish the line circuit.

It is contemplated to provide, in addition to the number of swords 218 corresponding to the elements of the code (for example, five or six if a five-unit or six-unit code is used), an extra

sword 218 responsive to the stop signal of a start-stop code. Since the stop signal is normally of marking nature, the sword 218 corresponding thereto assumes the position indicated in Fig. 12; but when the line circuit is broken or held open, the condition of the line during the stop interval is reversed or of spacing nature, whereupon the extra sword 218 assumes the position against stop 236 (Fig. 12) preparatory to operating contact 235.

Figs. 13, 14, and 15 illustrate additional modifications of platen phasing arrangements according to the present invention which are adapted to the structure disclosed in U. S. Patent 1,904,164. In the modification shown in Figs. 13 and 14, a function lever is selected by the setting of the vanes 75 in response to a predetermined test signal, whereupon the function lever 252 will be biased by its spring 253 about its pivot 254 to cause the rearward extension 255 to rotate an intermediate lever 256 about its pivot 257. Lever 256 in turn operates a lever 258 about its pivot 259 (Fig. 14) in a clockwise direction against the action of a spring 260 to close a contact pair 281 for completing a circuit extending from positive battery through resistance 262, over wire 263, through contact 261, over wire 264, and through the operating winding 265 of a relay 266, thence through resistance 267 to negative battery. This circuit may be completed only if the platen is out of phase; that is, in a position shown in Fig. 13. The alternative or "in phase" condition will be described hereinafter.

Upon the operation of relay 266, the armatures 268 and 269 thereof will be attracted. The operation of the armature 268 will act to break a contact 271 in the line circuit 272 which thereby indicates to the operator at the sending station that the platens at the interconnected stations are out of phase. The operation of armature 269 completes simultaneously a bell ringing circuit for bell 273 and a locking circuit for relay 266, the circuit for bell 273 extending from positive battery through a manual break switch armature 269, contact 274, winding of bell 273, through resistance 275 to negative battery, and the locking circuit for relay 266 extending from positive battery over armature 269 through contact 274, through locking winding 276, over wire 277, through contact 278, over wire 279 through resistance 267 to negative battery.

However, in the event that the platens are in phase, the platen phasing cam 281 will be so positioned as to permit the follower roller 282 to rest in the depression 283, whereupon lever 284 which carries the follower roller 282 will respond to the pull of spring 285 and be rotated in a clockwise direction, thereby moving bar 286 downwardly so that the stud 287 thereon will break or open the contact 278 in the locking circuit of relay 266 and close the contact 288 in the shunt circuit around the operating coil 265 of relay 266. This shunt circuit extends from positive battery, through resistance 262, over conductor 263, contact 261 (when closed momentarily upon the selective operation of function lever 252), contact 288 (when closed by stud 287), conductor 279, through resistance 267 to negative battery. Thus, if the platen 281 of the receiving printer is in its proper position when the test signal is sent over the line, the function lever 252 is selected and contact 261 is closed momentarily (during the cyclic period of operation of the apparatus). The relay 266 is not operated because follower roller 282 rests in depression

283, which permits bar 286, carrying stud 287, to be moved downwardly under tension of spring 285 until contact 278 is opened and contact 288 is closed. Closing contact 288 forms a shunt around the operating coil 265 of relay 266, thus causing the relay 266 to remain unoperated.

In the form of the invention shown in Fig. 15, a function lever 291 may respond to the proper signal setting therefor of vanes 75 under the action of its spring 292 to cause the rear extension 293 of the function lever to operate a bell crank lever 294 in a clockwise direction about its pivot 295 against the action of a spring 296. This will cause the disengagement of shoulder 297 from the horizontal extremity of a vertical bar 298 depending from arm 299 of a bail lever 301 pivotally carried on a pivot shaft 302 in the frame of the apparatus. Lever 301 is provided with an arm 303 carrying at its extremity a cam follower roller 304 which coacts with a platen phasing cam 305. The platen phasing cam 305 is shown in Fig. 15 in its phased position, in which position the disengagement of lever 294 from bar 298 will have no effect upon either a bell 306 or the signal line 307. In the event that the platen of the receiving printer is not in phase, the projection 308 of phasing cam 305 will be out of operative engagement with follower roller 304, permitting lever 301 to be rotated in a clockwise direction under the action of its spring 309 when shoulder 297 of lever 294 is disengaged from bar 298 in response to the operation of function lever 291 under the control of the remote sending station. When this happens, a contact 311 in the signal line circuit 307 will be opened through the instrumentality of projection 310 on bar 298, thus breaking the line circuit and indicating to the sending operator that the platens at the interconnected stations are out of phase. At the same time a contact 312 will be closed through the instrumentality of a stud 313 on bar 298, thus completing a bell ringing circuit for bell 306, which extends from positive battery through contact 312, resistance 314, winding of bell 306 to negative battery. Accordingly, it is noted that when the platen phasing cam 305 is in the position shown in Fig. 15, the selection of function lever 291 and operation of lever 294 will have no effect upon the platen phasing lever 301 and hence no indication is transmitted over signal line 307 to the sending operator.

The platen phasing arrangements herein described are particularly applicable to systems employing printed forms and sprocket feeding arrangements therefor. In the operation of such systems, a telegraph printer using a plurality of printed forms arranged in superimposed relation separated by duplicating means, it is essential that the leaves containing the printed forms be held in accurately aligned relation to each other so that the entries on the forms be made at their proper places on the forms even though the operation of the printer be continued without attention from an operator for a long period of time. In printing telegraph machines absolute accuracy in the positioning of the printing forms is essential because supervision is not contemplated for the purpose of making adjustments in the relative positions of the several sheets if such adjustments become necessary. If errors occur in aligning the sheets, such errors may even become cumulative; therefore, to prevent such an occurrence, the platen phasing means of the present invention permits the sending operator to test the interconnected printers to determine

whether the platens at each station are in proper phase relationship to each other.

In printers wherein is provided a shift and unshift position for the platen, the platen phasing arrangement is designed to be effective only when the platen is in the upper case position, and then only when the follower roller 282 for example (Fig. 13) rests in the depression in cam 281. In other words, the platen phasing arrangement will be effective only when the lever 284 (or lever 301, Fig. 15) assumes its furthest clockwise position. On the other hand, under the following three conditions, the platen phasing arrangement will not be effective, namely (1), when the platen is in the upper case or shift position and the follower roller 282 dwells on the high part of cam 281; (2), when the platen is in the lower case or unshift position and the follower roller 282 rests in the depression in cam 283, and (3), when the platen is in the latter position and the follower roller 282 dwells on the high part of cam 283. It is, of course, understood that although the noted three conditions apply specifically to Fig. 13, the same result is achieved by the form of the invention shown in Fig. 15, wherein the cam projection 308 is analogous in utility to the depression 283 of cam 281 in Fig. 13. In Fig. 13, a manually operable contact 270 is provided to break the locking and bell ringer circuits, comparable to contact 248 in Fig. 12. Arm 300 (Fig. 15) is a manual reset lever and provides a means whereby bar 298 may be manually restored to its latched position.

A sprocket feed means such as is adaptable to printers herein described is shown in Fig. 16 and is fully described in U. S. Patent 1,884,760 issued to R. A. Lake. In this illustration, the platen is indicated at 95 and is provided with sprocket teeth 315 at each end arranged around the periphery thereof. These sprocket teeth mesh with marginal holes 316 in the record material composed of printed forms. Mounted on the platen shaft 94 and secured to platen 95 is the platen phasing cam 305, shown also in Fig. 15. The application of the structure shown in Fig. 16 to the structures previously disclosed is readily discernible.

The embodiments disclosed herein are to be taken as illustrative and not restrictive, and it is understood that the various features of the invention are capable of embodiment in many and varied applications other than those specifically disclosed, without departure from the spirit and scope of the invention as defined in the appended claims.

What is claimed is:

1. In a telegraph machine, a selecting mechanism comprising a series of vanes, an element selected by said vanes, a transmitting mechanism for transmitting code combinations of impulses, and a key lever in said transmitting mechanism actuated mechanically by said element to cause said transmitting mechanism to transmit a code combination of impulses.

2. In a telegraph apparatus, electrical transmitting contacts, a key lever and associated mechanical parts engaging said contacts to control said contacts in code manner when said key lever is operated, a telegraph receiver having selectable members and signal responsive devices controlling selection of one of said members, and mechanical linkage between said one of said selectable members and said key lever whereby operation of said member effects operation of said key lever.

3. In a printing telegraph system, a plurality of stations, a transmitting and a receiving mechanism at each station, means associated with each station for interrupting effective transmission

5 from a remote transmitting station and invariably and automatically conditioning the receiving mechanism at the said transmitting station for message reception purposes, and means at the interrupted station effective under the control of said interrupting station for automatically reconditioning the transmitting mechanism at said interrupted transmitting station.

4. In a page printing telegraph machine, a normally effective line feed mechanism, an ejecting mechanism, and severing means controlled by said ejecting mechanism, said severing means effective when operated to disable said line feed mechanism and simultaneously to effectuate the actuation of said ejecting mechanism.

5. In a telegraph system comprising a plurality of stations, printing telegraph apparatus at each station interconnected for communication including sheet feeding mechanism, and means responsive to a predetermined signal when said mechanism is in a predetermined position for transmitting to another connected station a condition indicative of said position.

6. In a printing telegraph system, a plurality of intercommunicating stations, a combination sending and receiving instrument at each station, each instrument including a selector mechanism responsive to received code combinations of signalling impulses transmitted from any one of said plurality of stations, a plurality of elements selectively operated by said selector mechanism, a member selectively controlled by said plurality of elements and effective under certain predetermined conditions to control monitory functions, a platen, and means controlled by said platen to determine the effectiveness of said member.

7. In a printing telegraph apparatus, a selector mechanism responsive to code combinations of signalling impulses, a set of elements selectively operated by said selector mechanism, 45 a member responsive to a predetermined setting of said elements to control monitory functions, a platen, and means controlled by said platen to determine the effectiveness of said member.

8. In a telegraph system comprising a plurality of intercommunicating stations, a receiving instrument at each station, a selecting mechanism in each receiving instrument responsive to code signal impulses comprising a plurality of selector members, and means to perform functions including a plurality of function code bars to be controlled directly by said members, said means including cutting apparatus effective automatically after a predetermined number of operations of a certain one of said bars.

9. In a telegraph system, a plurality of intercommunicating stations, a combination sending and receiving instrument at each station, a selector mechanism in each receiving instrument responsive to code signal impulses comprising a plurality of selector members, a function element selectively controlled by said members, a platen, and means effective under the joint control of said element and said platen to control the transmission of a code signal.

10. In a telegraph system comprising a plurality of intercommunicating stations, a receiving instrument at each station, a selecting mechanism in each receiving instrument responsive to code signal impulses comprising a plurality of

75

selector members, a plurality of function code bars selectively controlled by said selector members, and paper feeding means comprising a plurality of independently releasable feeding units controlled directly by one or more of said code bars under the control of a remote station.

11. In a page printing telegraph machine, a normally effective line feed mechanism, a constantly effective ejecting mechanism, and cutting means controlled by said ejecting mechanism, said cutting means comprising an electromagnetically operated means effective under certain operating conditions to disable said line feed mechanism and simultaneously to effectuate the actuation of said ejecting mechanism and said cutting means.

12. In a page printing telegraph machine, a normally effective line feed mechanism, a constantly effective ejecting mechanism, and cutting means controlled by said ejecting mechanism, said cutting means comprising means effective under certain operating conditions for disabling said line feed mechanism and simultaneously effectuating the actuation of said ejecting mechanism and said cutting means.

13. In a printing telegraph system, a plurality of intercommunicating stations, a combination sending and receiving instrument at each station, each instrument including a selector mechanism responsive to received code combinations of signalling impulses transmitted from any one of said stations, a plurality of elements selectively operated by said mechanism, an interponent, platen controlled means, switching means, a function lever selectively controlled by said elements, and means controlled by said platen controlled means to render said function lever effective to establish through said interponent a change in said switching means.

14. A printing machine feeding and aligning mechanism for forms having feeding perforations adjacent their edges, comprising rotary aligning means provided with pins to enter successive perforations in said form to bring the perforations therein into registry, a cam definitely related to said rotary aligning means, an element operable under certain operating conditions, and means conditioned under the joint control of said cam and said element to supervise monitory functions.

15. In a telegraph system, a plurality of intercommunicating stations, a combination sending and receiving instrument at each station, a selecting mechanism in each receiving instrument responsive to code signal impulses comprising a plurality of selector members, means to perform functions including a plurality of function code bars to be controlled directly by said members, platen controlled means, and means effective under the joint control of said platen controlled means and one of said function code bars to transmit a code signal.

16. In a page printing telegraph machine, signal controlled means, an ejecting mechanism, cutting means, and means included in said ejecting mechanism effective automatically after a predetermined range of effectiveness of said signal controlled means to control the operation of said cutting means.

17. In a page printing telegraph machine, signal controlled means, an ejecting mechanism, an electromagnetically operated cutting means, and contact means included in said ejecting mechanism effective automatically after a predetermined range of effectiveness of said signal con-

trolled means to control the operation of said cutting means.

18. In a telegraph printer, a platen controlled phasing means, a multiple feeding means, an auxiliary feeding means, a selecting mechanism responsive to code signals comprising a plurality of selector members, means to perform functions other than recording including a plurality of function code bars to be controlled directly by said members, and means actuated by said code bars to control jointly or severally said phasing, multiple feeding, and auxiliary feeding means.

19. In a printing telegraph machine, a plurality of paper feeding devices, selecting mechanism responsive to code signals comprising a plurality of selector members, means to perform functions other than recording including a plurality of function code bars controllable directly by said members, and means actuated by said code bars to control in varying combinations said paper feeding devices.

20. In a telegraph system, a plurality of inter-communicating stations, a combination sending and receiving instrument at each station, a selecting mechanism in each receiving instrument responsive to code signals comprising a plurality of selector members, means to perform functions other than recording including a plurality of function code bars controllable directly by said members, platen controlled means, and means effective under the joint control of said platen controlled means and one of said function code bars to establish a predetermined condition between said stations.

21. In a telegraph machine, a selecting mechanism, an operating element selected by said mechanism, a transmitting mechanism for transmitting code combinations of impulses, and a key lever in said transmitting mechanism actuated mechanically by said element to cause said transmitting mechanism to transmit a code combination of impulses.

22. In a printing telegraph system, a plurality of interconnected stations, a transmitting and a receiving apparatus at each station convertible from sending to receiving and vice versa, means associated with each apparatus acting to convert automatically the other apparatus from sending to receiving, and means to cause said other apparatus to be reconverted automatically from receiving to sending in response to a predetermined code signal.

23. In a combination sending and receiving telegraph apparatus, a selector mechanism, a plurality of elements selectively operated by said mechanism, a first function lever selectively operated by said elements, switching means effective to condition the apparatus for sending or receiving purposes, means operable by said first function lever to operate said switching means to effect the conversion of the apparatus from a sending to a receiving instrument, a second function lever selectively operated by said elements, and means operable by said second function lever to operate said switching means to effect the reconversion of the apparatus from a receiving to a sending instrument.

24. In a combination sending and receiving telegraph apparatus, a selector mechanism, a plurality of elements selectively operated by said mechanism, a first function lever selectively operated by said elements, switching means effective to condition the apparatus for sending or receiving purposes, a system of T-levers operable

by said first function lever to operate said switching means to effect the conversion of the apparatus from a sending to a receiving instrument, a second function lever selectively operated by said elements, and an interponent operable by said second function lever to operate said switching means to effect the reconversion of the apparatus from a receiving to a sending instrument.

25. In a combination sending and receiving telegraph apparatus, transmitting means, a series of key levers for controlling said means, a selector mechanism, a plurality of elements selectively operated by said mechanism, a first function lever selectively operated by said elements, switching means effective to condition the apparatus for sending or receiving purposes, means operable by said first function lever to operate said switching means to effect the conversion of the apparatus from a sending to a receiving instrument, a second function lever selectively operated by said elements, and means operable by said second function lever to operate said switching means to effect simultaneously the reconversion of the apparatus from a receiving to a sending instrument and, through the instrumentality of one of said key levers, to transmit a code combination of impulses.

26. In a combination sending and receiving telegraph apparatus, transmitting means, a series of key levers for controlling said means, a selector mechanism, a plurality of elements selectively operated by said mechanism, a plurality of function levers selectively operated by said elements, switching means effective to condition the apparatus for sending or receiving purposes, means operable by one of said function levers to operate said switching means to effect the conversion of the apparatus from a sending to a receiving instrument, a platen controlled means, and means effective under the joint control of said platen controlled means and another of said function levers to operate said switching means to effect concurrently the reconversion of the apparatus from a receiving to a sending instrument and, through the instrumentality of one of said key levers, to transmit a code signal.

27. In a combination sending and receiving telegraph apparatus, a selector mechanism, a plurality of elements selectively operated by said mechanism, a plurality of function levers selectively operated by said elements, switching means effective to condition the apparatus for sending or receiving purposes, means operable by one of said function levers to operate said switching means to effect the conversion of the apparatus from a sending to a receiving instrument, a platen controlled means, and means effective under the joint control of said platen controlled means and another of said function levers to effect the conversion of the apparatus from a receiving to a sending instrument.

28. In a printing telegraph system, a plurality of stations, a combination sending and receiving apparatus at each station, each apparatus including a selector mechanism responsive to received code combinations of signalling impulses, a send-receive switch, and a solely mechanical interconnection between said mechanism and said switch to render said apparatus automatically interchangeable from the sending to a receiving position or vice versa.

29. In a printing telegraph system, a plurality of stations, a combination sending and receiving apparatus at each station, each apparatus including a selector mechanism responsive to re-

ceived code combination of signalling impulses, a send-receive switch, a solely mechanical interconnection between said mechanism and said switch to render said apparatus automatically interchangeable from the sending to a receiving position, platen controlled means, and means effective under the control of said platen controlled means to render said apparatus automatically interchangeable from the receiving to a sending position.

30. In a printing telegraph system, a plurality of stations, a combination sending and receiving apparatus at each station, each apparatus including a selector mechanism responsive to received code combinations of signalling impulses, a send-receive switch, a circuit breaker, mechanical interconnection between said mechanism and said switch, means effective upon actuation of said circuit breaker to effect through said mechanical interconnection the transposition of the apparatus from the send to the receive position, and means also effective through said mechanical interconnection to render the apparatus interchangeable from the receive to the send position.

31. In a printing telegraph system, a plurality of stations, a combination sending and receiving apparatus at each station, each apparatus including a selector mechanism responsive to received code combinations of signalling impulses, a send-receive switch, a circuit breaker, mechanical interconnection between said mechanism and said switch, means effective upon actuation of said circuit breaker to effect through said mechanical interconnection the transposition of the apparatus from the send to the receive position, platen controlled means, and means effective through said mechanical interconnection under the control of said platen controlled means to effect the transposition of the apparatus from the receive to the send position.

32. In a communicating system, a plurality of stations, transmitters and recorders at each station, a control device associated with each transmitter, means in each recorder operable under the control of said device for rendering at each station the receiving apparatus effective and the transmitting apparatus ineffective, and further means in each recorder operable under control of said device for rendering at each station the transmitting apparatus effective and the receiving apparatus ineffective.

33. In a communicating system, a plurality of stations, transmitters and recorders at each station, a control device associated with each transmitter, means in each recorder operable under the control of said device for rendering at each station the receiving apparatus effective and the transmitting apparatus ineffective, platen controlled means, and further means in each recorder operable under the joint control of said platen controlled means and said device for rendering at each station the transmitting apparatus effective and the receiving apparatus ineffective.

34. In a printing telegraph system, a plurality of stations, a transmitting and a receiving mechanism at each station, mechanically operated means associated with each station for interrupting effective transmission from a remote transmitting station for invariably and automatically conditioning the receiving mechanism at the said transmitting station for message reception purposes, and means associated with said mechanically operated means for reestablishing

effective transmission from said remote transmitting station for invariably and automatically reconditioning the transmitting mechanism at said transmitting station for message transmission purposes.

35. In a telegraph apparatus, electrical transmitting contacts, a key lever and associated mechanical parts engaging said contacts to control said contacts in code manner when said key lever has been operated, a telegraph receiver having power driven members and signal responsive devices controlling selection of one of said members, and mechanical linkage between said one of said power driven members and said key lever whereby operation of said member effects operation of said key lever.

36. In a page printing telegraph machine, signal controlled means, an ejecting mechanism, an electromagnetically operated cutting means, contact means included in said ejecting mechanism effective automatically after a predetermined range of effectiveness of said signal controlled means to initiate the operation of said cutting means, and means interposed between said cutting means and said contact means responsive to said initiation to consummate the operation of said cutting means.

37. In a page printing telegraph machine, signal controlled means, an ejecting mechanism, an electromagnetically operated cutting means, contact means included in said ejecting mechanism effective automatically after a predetermined range of effectiveness of said signal controlled means to initiate the operation of said cutting means, and relay means interposed between said cutting means and said contact means responsive to said initiation to consummate the operation of said cutting means.

38. In a page printing telegraph machine, signal controlled means, an ejecting mechanism, an electromagnetically operated cutting means, and tangentially co-operative rings included in said ejecting mechanism effective automatically after a predetermined range of effectiveness of said signal controlled means to control the operation of said cutting means.

39. In a page printing telegraph machine, signal controlled means, a pair of constantly rotating pressure rollers for performing ejecting functions, cutting means and means co-operatively associated with said rollers and effective automatically after a predetermined range of effectiveness of said signal controlled means to control the operation of said cutting means.

40. In a page printing telegraph machine, signal controlled means, a pair of ejector rollers, tangentially co-operative rings carried by said rollers, cutting means, and means co-operatively associated with said rings and effective automatically after a predetermined range of effectiveness of said signal controlled means to control the operation of said cutting means.

41. In a page printing telegraph machine, a plurality of paper feeding devices, signal responsive means, a plurality of rockable vane members permutably controlled by said means, a series of function code bars controllable by said members, and means actuated by said code bars to control in varying combinations said paper feeding devices.

42. In a page printing telegraph machine, a plurality of paper feeding devices, means individual to each device for subjecting said device to a constant torque, release means associated with each of said means, a signal responsive

means, a plurality of rockable vane members permutably controlled by said means, a series of function code bars controllable by said members, and means actuated by said code bars to control in varying combinations said release means.

43. In a printing telegraph machine, a plurality of feeding devices, means individual to each device for subjecting said device to a constant torque, release means associated with each of said means, selecting mechanism responsive to code signals comprising a plurality of selector members, a plurality of function code bars controllable by said members, and means actuated by said code bars to control in varying combinations said release means.

44. In a printing telegraph machine, a plurality of feeding devices, a common driving means, means individual to each of said devices and operatively associated with said driving means for subjecting each of said devices to a constant torque, release means associated with each of said individual means, selecting mechanism responsive to code signals comprising a plurality of selector members, a plurality of function code bars controllable by said members, and means actuated by said code bars to control in varying combinations said release means.

45. In a telegraph system comprising a plurality of intercommunicating stations, a receiving instrument at each station, a selecting mechanism in each receiving instrument responsive to code signal impulses comprising a plurality of selector members, a plurality of function code bars selectively controlled by said selector members, a plurality of paper feeding devices, means individual to each device for subjecting said device to a constant torque, release means associated with each of said means, and means actuated by said code bars under the control of a remote station to control in varying combinations said release means.

46. In a telegraph printer, a platen, an all-mechanical phasing means therefor, plural-step feeding means, single-step feeding means, a selecting mechanism responsive to code signals comprising a plurality of selector members, means to perform functions other than recording including a plurality of function code bars to be controlled by said members, and means actuated by said code bars to control jointly or severally said phasing and said feeding means.

47. In a telegraph printer, a platen controlled phasing means, form feeding means, line feeding means, a selecting mechanism responsive to code signals comprising a plurality of selector members, means to perform functions other than recording including a plurality of function code bars to be controlled by said members, and means actuated by said code bars to control jointly or severally said phasing, form feeding, and line feeding means.

48. In a telegraph printer, a platen controlled phasing means, a multiple feeding means, an auxiliary feeding means, a signal responsive means, a plurality of selector vanes permutably controlled by said signal responsive means, a series of function code bars controllable by said vanes, and means actuated by said code bars to control jointly or severally said phasing, multiple feeding, and auxiliary feeding means.

49. In a telegraph printer, a platen controlled phasing means, form feeding means, line feeding means, a signal responsive means, a plurality of selector vanes permutably controlled by said signal responsive means, a series of function code

bars controllable by said vanes, and means actuated by said code bars to control jointly or severally said phasing, form feeding, and line feeding means.

50. In a telegraph printer, a platen, an all-mechanical phasing means therefor, form feeding means, line feeding means, a signal responsive

means, a plurality of selector vanes permutably controlled by said signal responsive means, a series of function code bars controllable by said vanes, and means actuated by said code bars to control jointly or severally said phasing, form-feeding, and line feeding means.

ALBERT H. REIBER.
